Attn:

UNITED STATES PATENT OFFICE

FRITZ WASCHICZECK, OF NAUMBURG, GERMANY, ASSIGNOR OF ONE-HALF TO THE
FIRM OTTO SCHUBERT & SOHN, OF NAUMBURG, GERMANY

SEPARABLE FASTENER

Application filed July 23, 1929, Serial No. 380,274, and in Germany December 10, 1928.

The present invention relates to a separable fastener construction comprising separable metallic fasteners particularly those of the type known as multiple operated fasteners which are adapted to be arranged in rows along the longitudinal edges of contiguous portions of pieces of fabric and to be interlocked and released upon operation of a manually movable slide. Fasteners of this type are ordinarily clamped or attached to a reinforced edge of a strip of fabric in such a way that portions of the fasteners extend beyond the edge of the fabric, said projecting or free portions being configured to coact with corresponding free or projecting fastener elements carried at the edge of a corresponding strip of fabric to establish an interlock between the two. The top and bottom surfaces of the fastener elements are elevated with relation to the fabric at those portions of the fastener elements which are anchored in the fabric, this elevated portion being engaged by a slide member operable upon movement in one direction to cause the elements to interlock and, upon movement in the other direction, to cause the release of such elements. The slide member, as shown for example in Patent No. 1,243,458 and others of a similar type, is provided in its interior with cam surfaces to assure the establishment in every position of the slide of an angular relation between the free ends of the fastener elements appropriate to cause an interlocking or an unlocking within the slide of the elements according to the direction in which the slide is being moved. Fasteners of this kind have gone into extensive use, but for many purposes and in many ways they are not entirely satisfactory. For example, as the fastener elements are usually exposed to view, they have failed to again favor wherever neatness and beauty were of prime importance as in ladies' hand bags, garments, etc. Since the fastener elements are exposed, they must be made of rust-proof material or be plated with an oxidation and friction-resisting metal which greatly increases the cost of manufacture. Furthermore, when such fasteners are used in connection with articles which, as

in the case of over-shoes, are subjected to clogging by dirt or ice, proper operation of the slide is frequently interfered with.

To overcome such difficulties it has been heretofore proposed to provide flaps adapted to overlie the fastener elements, so that they might be covered in the interlocked position. In such constructions the flaps were attached either to the fabric strip on which the fastener elements were mounted, beyond the attached edges of the latter, or to the material (such as the upper part of an over-shoe) to which the fabric strips were connected. In such arrangements the slide engages the elevated edges of the fastener elements (as in the older exposed type of fasteners) and is positioned between such elements and the covering flaps so that the upstanding lug to which the slide-operating finger piece is generally attached lies between and engages the edges of the flaps. In such constructions the repeated movement of the slide and of the upstanding lug thereof tended to fray the flaps and to urge the flaps away from the rows of fastener elements and to cause the contiguous flap edges to curl away from each other so that a continuing nice fit between the flaps was rendered impossible and the fastener elements remain at least in part constantly exposed while the combined structure exhibited an unsightly appearance.

It is an object of the present invention to provide a combination wherein fastener elements of the indicated type are reliably, effectively, and permanently enclosed and protected by a tough esthetically appearing material which will not only permit proper operation of the metallic fastener elements but will tend to assure stability of their relative positions and persistence of proper operating conditions so that the device will not be unfavorably affected, notwithstanding repeated operation of the slide. In particular, it is an object of the present invention to provide a fastener strip construction of such a nature that a protecting material is closely associated with the fastener elements so as to cover their roots while extending part way over their free ends, preferably to such an

extent that upon interlock of mating fastener elements the free edge portion of the covering material carried by the two strips will make contact with each other. It is also an 5 object of the present invention to equip fastener strips of the kind in question with a reliable protective covering material which functions operatively between the planes of the upper and lower inner surfaces of the 10 slide, so that the slide embraces and travels over the whole of the protective material instead of moving beneath any flaps or exterior coverings.

It is also an object of the present invention 15 to provide separable strips with covering material which will serve to reinforce the fabric-attached portions of the fastener elements and will provide a resilient mass entirely enclosing the roots of the fastener elements and 20 simultaneously serving to maintain and to re-establish the position of the fastener elements with relation to the fabric. In the preferred form of the invention the covering material is composed of rubber which is vulcanized 25 upon the roots of the fastener elements and to the supporting fabric strip, so that the roots of the elements are embedded in the rubber mass while the free ends of the covering material overlie a portion of the free ends of 30 the fastener elements being separated therefrom, however, to permit the necessary movement of the interlocking portions of the fastener elements during the process of locking or unlocking.

35 It is a further object of the present invention to provide a covered fastener element strip which is neat and substantially flat in appearance and capable of ornamental and decorative treatment, so that the same may 40 be used with satisfaction on high grade articles and in conspicuous places, the covering material being capable of treatment to cause it to harmonize with the material of the article to which it is applied. It is a feature 45 of the present invention that the metal of which the fastener elements are composed need not be electro-plated or provided with a corrosion-resisting surface, since the metal elements of which the fasteners are made are 50 completely enclosed or concealed, so that they can be made of brass or similar material without interfering with the effectiveness or sightliness of the product.

An embodiment of the invention is illustrated 55 by way of example in the accompanying drawings in which Fig. 1 shows in top plan view a separable fastener constructed in accordance with the present invention and in partially opened position, while Fig. 2 is a 60 section on line A—B of Fig. 1.

The numerals 1—1 indicate a strip of fabric of any suitable type provided with a reinforced edge to which the fastener elements 3 are attached in any known manner. The 65 fabric strips 1 are designed to be sewn or

otherwise attached to a longitudinal edge of an opening in a garment or other article, which opening is to be opened or closed at will by the operation of the slide 4.

In the preferred form of the present invention the rows of fastener elements 3 are encased at the roots thereof by a pliable covering substance, such as rubber, vulcanized upon said fastener elements, and upon the fabric, and forming the strips 2—2 which, 70 as illustrated in Fig. 2, are of substantially rectangular cross-section. As shown in Fig. 1 these strips 2 extend in the direction of the free ends of the fastener elements but terminate at their free edges before reaching the extreme free ends of the fastener elements. These free ends of the covering material are disconnected from the forward or free ends of the fastener elements, while at the root 75 ends of the fastener elements the covering material completely encloses and is attached to the fastener elements. The resilient or elastic covering material is thus positioned directly upon and between the roots of the fastener elements 3. When the cover strips 2 are made of rubber or similar material, 80 they may be vulcanized into a continuous, homogeneous structure which thereby becomes permanently attached to the fastener-elements-supporting strip or base 1 and to the 85 roots or attached portions of the fastener elements. In this manner an effective reinforcement for the fastener elements is provided, so that loosening of such elements 90 after continuous use, is prevented.

As indicated in Fig. 2, the cover strips are so formed that they provide a raised face rising from the supporting strip 1, said face functioning as a guide for the slide 4 and aiding it in its movement. Due to the fact that the slide thus engages a continuous strip of soft but tough material such as vulcanized rubber, the action of the slide is very smooth and practically noiseless. It will also be clear from Fig. 1 that a portion of the slide 100 passes between the abutting edges of the rubber strips to cause engagement and disengagement of the fastener elements, yet the slide at all times tends to keep the rubber strips flat and prevents their curling away 105 from each other.

The cover strips can be made very flat and as they may consist of rubber or similar plastic material which is not unpleasant to the touch and is a poor conductor of heat, 110 the new fastener strip can be comfortably employed in undergarments or the like. Due to the method of construction involved in the new strip, there are no rough or cutting or abrading surfaces such as were frequently 115 found objectionable in the old style exposed fasteners. When the new fastener strip is employed in overshoes there is no danger of dirt or ice reaching the fasteners and clogging the same, because the contiguous edges 120

of the cover strips always remain in substantially complete contact as well as in perfect alignment. Because of its smooth action the slide need not be made as strong as was heretofore necessary. The material of which the fasteners are constructed may be of brass or other inexpensive material. The slide may be made of an ornamental design in harmony with the design of the fastener strip 16 or the article in connection with which the strips are used. Variations may obviously be resorted to within the scope of the invention and without departing from its spirit.

I claim:

15 1. A separable fastener, comprising, in combination, two opposite fabric edges, two opposite groups of fastener elements supported respectively on said fabric edges and adapted to engage with one another, a cover 20 of elastic material on each fabric edge and on each group of fastener elements at the attached portions of said elements, and there filling the gaps between said elements and extending at least partly over the free ends 25 of the latter, and a slide gripping over said covers of the opposite groups of fastener elements.

2. A separable fastener, as specified in claim 1, wherein said covers are made of 30 rubber and are vulcanized to the fabric.

3. The combination with a pair of adjacent rows of fastener elements adapted to be interlocked with each other to close an opening therebetween and a supporting base for each 35 of said rows of elements, such supporting bases lying in substantially the same plane, of a section of pliable material attached to the supporting base and to the roots of the elements attached to said base, said pliable 40 material overlying each of said rows of elements and being of such width and so related as to cover completely, in abutting relation, both rows of fastener elements when the latter are interlocked, and a slide engaging over 45 said sections of pliable material and adapted, when moved, to pass over the whole of said pliable material.

4. A fastener structure of the interlocking, slide-operated type, comprising supporting 50 strips having confronting strip edges, lying in substantially the same plane, a row of fastener elements on each of the confronting strip edges, a strip of pliable protecting material overlying root portions of the fastener elements in each row, and an operating slide 55 embracing the rows of elements and overlying said strips of pliable material.

5. A fastener structure of the interlocking slide-operated type, comprising supporting 60 edges having confronting fabric edges, a row of fastener elements permanently attached to each of the confronting fabric edges, an elastic protecting strip of rubber cemented to the fabric edges and to the root portions of 65 the fastener elements in each row, so as to

form a permanent union between the fastener elements and the fabric, and an operating slide embracing the rows of elements and substantially enclosing said strips of protecting material.

70

6. A fastener structure of the interlocking slide-operated type comprising supporting strips having confronting strip edges, a row of fastener elements on each of the confronting strip edges, a strip of pliable protecting material overlying in attached relation the root portions of the fastener elements in each row and overlying in unattached relation a part of each of the fastener elements extending from the strip edges and extending toward but not quite up to the free end portions of the fastener elements and an operating slide 75 embracing the rows of elements and overlying said strips of pliable material.

80

7. A fastener structure of the interlocking, slide-operated type, comprising supporting strips having confronting strip edges lying in substantially the same plane, a row of fastener elements on each of the confronting strip edges, a strip of pliable protecting material overlying root portions of the fastener elements in each row, and an operating slide 85 having members overlying and substantially enclosing the rows of fastener elements and the whole of the pliable strips so that during slide movement the elements and the pliable strips pass within the slide.

90

8. A fastener structure of the interlocking, slide-operated type, comprising supporting strips having confronting strip edges, a row of fastener elements on each of the confronting strip edges, a strip of pliable protecting material overlying root portions of the fastener elements in each row, and an operating slide 100 embracing the rows of elements and overlying said strips of pliable material, inward edges of the pliable strip being located to expose only short free end portions of the fastener elements to permit interlocking.

105

9. A fastener structure of the interlocking, slide-operated type, comprising supporting strips having confronting strip edges, a row of fastener elements on each of the confronting strip edges, a strip of pliable protecting material overlying root portions of the fastener elements in each row, an operating slide 110 embracing the rows of elements and overlying said strips of pliable material, inward edges of the pliable strips being so located as to expose only short free end portions of the fastener elements to permit interlocking and so as to cause said strip edges to be brought into engagement when the structure is in locked condition.

115

10. A fastener structure of the interlocking, slide-operated type, comprising supporting strips having confronting strip edges lying in substantially the same plane, a row of fastener elements on each of the confronting strip edges, a strip of pliable protecting ma- 120
125
130

- aterial overlying root portions of the fastener elements in each row, and an operating slide having members overlying and substantially enclosing the rows of fastener elements and the pliable strips so that during slide movement the elements and pliable strips pass within the slide, inward edges of the protecting strips being located to expose only short free end portions of the fastener elements to permit interlocking and so that said strip edges are brought into engagement when the structure is in locked condition.
11. A fastener structure of the interlocking, slide-operated type, comprising fabric base strips lying in substantially the same plane, a row of fastener elements on an edge of each strip, the root portions of said elements being engaged on the strip and interlocking formations of the elements projecting from the strip edge, an enclosing and protecting strip of flexible material overlying and substantially enclosing the root portions of each row of fastening elements, and an operating slide having members formed to produce interlocking action and to substantially embrace the rows of fastening elements and the protecting strips which move within and through the slide as the latter is operated.
12. A fastener structure of the interlocking, slide-operated type, comprising fabric base strips lying in substantially the same plane, a row of fastener elements on an edge of each strip, the root portions of said elements being engaged on the strip and interlocking formations of the elements projecting from the strip edge, an enclosing and protecting strip of flexible material overlying and substantially enclosing the root portions of each row of fastening elements, and an operating slide having members formed to produce interlocking action and to substantially embrace the rows of fastening elements and the protecting strips which move within and through the slide as the latter is operated.
13. A fastener structure of the interlocking, slide-operated type, comprising fabric base strips, a row of fastener elements on an edge of each strip, the root portions of said elements being engaged on the strip and interlocking formations of the elements projecting from the strip edge, an enclosing and protecting strip of flexible material overlying and substantially enclosing the root portions of each row of fastening elements, and an operating slide having members formed to produce interlocking action and to substantially embrace the rows of fastening elements and the protecting strips which move within and through the slide as the latter is operated, the protecting strips being of a width to overlie longitudinal zones of the base strips adjacent the roots of the fastener elements.
14. A fastener structure of the interlocking slide-operated type, comprising fabric base strips, a row of fastener elements on an edge of each strip, the root portions of said elements being engaged on the strip and interlocking formations of the elements projecting from the strip edge, an enclosing and protecting strip of flexible material inherently enclosing the root portions and having an extension section overlying all the unenclosed portions of the fastener element except the free tip ends thereof and an operating slide having members formed to produce interlocking action and to substantially embrace the rows of fastening elements and the protecting strips which move within and through the slide as the latter is operated.
15. A fastener structure of the interlocking slide-operated type, comprising fabric base strips, a row of fastener elements on an edge of each strip, the root portions of said elements being engaged on the strip and interlocking formations of the elements projecting from the strip edge, a strip of rubber composition overlying and substantially enclosing the root portions of each row of fastening elements and cemented to said root portions and to the adjacent fabric strip portions to assist in holding said fastener elements in proper spaced relation, and an operating slide having members formed to produce interlocking action and to substantially enclose or embrace the rows of fastening elements and the rubber strips which move within and through the slide as the latter is operated.
16. A fastener structure of the interlocking slide-operated type, comprising fabric base strips, a row of fastener elements on an edge of each strip, the root portions of said elements being engaged on the strip and interlocking formations of the elements projecting from the strip edge, a strip of rubber composition overlying and substantially enclosing the root portions of each row of fastening elements and cemented to said root portions and to the adjacent fabric strip portions to assist in holding said fastener elements in proper spaced relation, and an operating slide having members formed to produce interlocking action and to substantially enclose or embrace the rows of fastening elements and the rubber strips which move within and through the slide as the latter is operated, the rubber strips being of a width to overlie longitudinal zones of the base strips adjacent the roots of the fastener elements.
17. A fastener structure of the interlock-

- ing slide-operated type, comprising fabric base strips, a row of fastener elements on an edge of each strip, the root portions of said elements being engaged on the strip and interlocking formations of the elements projecting from the strip edge, a strip of rubber composition overlying and substantially enclosing the root portions of each row of fastening elements, and an operating slide having members formed to produce interlocking action and to substantially enclose or embrace the rows of fastening elements and the rubber strips which move within and through the slide as the latter is operated, the rubber strips being of a width to overlie longitudinal zones of the base strips adjacent the roots of the fastener elements, and the free edges of the protecting strips being adjacent the free end portions of the fastener elements and positioned to be brought into firm engagement when the structure is in locked condition.
18. A fastener structure of the interlocking slide-operated type, comprising fabric base strips, a row of fastener elements on an edge of each strip, the root portions of said elements being engaged on the strip and interlocking formations of the elements projecting from the strip edge, a strip of rubber composition enclosing the root portions and having an extension section overlying all the unenclosed portions of the fastening elements except the free tip ends of each row and an operating slide having members formed to produce interlocking action and to substantially enclose or embrace the rows of fastening elements and the rubber strips which move within and through the slide as the latter is operated.
19. A fastener structure of the interlocking, slide-operated type, comprising supporting strips lying in substantially the same plane a row of fastener elements on each of the fronting strip edges, a strip of pliable protecting material of substantially rectangular cross-section and overlying root portions of the fastener elements in each row and cemented to said root portions and to the adjacent fabric strip portions to assist in holding said fastener elements in proper spaced relation, and an operating slide embracing the rows of elements and overlying said strips of pliable material.
20. A fastener structure of the interlocking, slide-operated type, comprising fabric base strips lying in substantially the same plane, a row of fastener elements on an edge of each strip, the root portions of said elements being engaged on the strip and interlocking formations of the elements projecting from the strip edge, an enclosing and protecting strip of flexible material of substantially rectangular cross-section overlying and substantially enclosing the root portions of each row of fastening elements, and cemented to said root portions and to the ad-
- jaacent fabric strip portions to assist in holding said fastener elements in proper spaced relation and an operating slide having members formed to produce interlocking action and to substantially embrace the rows of fastening elements and the protecting strips which move within and through the slide as the latter is operated.
21. In combination with an interlocking fastener of the type disclosed, comprising base strips lying in substantially the same plane, rows of fastener elements thereon and an operating slide, strips of flexible material on the base strips and overlying root portions of the fastener elements, the slide being formed to substantially enclose the flexible strips which move through it as it is operated.
22. A fastener structure of the interlocking slide-operated type, comprising supporting strips having confronting strip edges lying in substantially the same plane, a row of fastener elements on each of the confronting strip edges, pliable protecting material supported from each of the confronting strips, and an operating slide embracing the rows of elements and so much of the pliable material as can be accommodated by the slide, whereby when the slide is in operation it will successively embrace and pass over continuous sequences of the fastener elements and successive portion of the pliable material.
23. A fastener structure of the interlocking, slide-operated type, comprising supporting strips having confronting strip edges, a row of fastener elements on each of the confronting strip edges, a strip of pliable material overlying root portions of the fastener elements in each row and an operating slide having passages therethrough for the fastener elements as well as for the protecting material, said passages being composed of a channel longitudinal of the rows of fastener elements and of two connecting channels extending angularly from the longitudinal channel, said channels being so dimensioned that the angular channels are approximately equal in cross-sectional dimensions to the cross-sectional area of the protecting material and the fastener elements extending therefrom, while the longitudinal channel approximates in cross-section the area of the cross-section of the two strips of pliable material situated on the opposite confronting strip edges of the supporting strips.
24. A fastener structure of the interlocking, slide-operated type, comprising supporting base strips, a row of fastener elements at an edge of each of said strips, a strip of pliable protecting material overlying root portions of the fastener elements in each row and attached along one edge to said base strips, the other edges of said protecting strips being free, said latter strips being so dimensioned that when the rows of fastener elements are interlocked the free ends of such

strips engage each other in abutting relation, and an operating slide embracing the rows of fastener elements and overlying said strips of pliable material.

25. A fastener structure as set forth in claim 24, wherein the fastener elements project beyond the free edges of the protecting strips and wherein the slide includes a fastener separating member arranged to engage

10 the ends of the fastener elements during the opening movement without engaging the free edges of said protecting strips.

26. A fastener structure of the interlocking slide-operated type comprising supporting

15 base strips, a row of fastener elements attached near an edge of each of said strips, a strip of pliable protecting material connected with such strips, and overlying portions of the fastener elements in each row and terminating in free edges, said protecting strips being so dimensioned that when the rows of

20 fastener elements are interlocked the free edges of the protecting strips engage each other in abutting relation, and an operating

25 slide embracing both the rows of fastener elements and said strips of pliable material.

27. A fastener structure comprising two supporting strips, each having associated therewith, at both sides adjoining one of its

30 edges, thickened sections of rubber-like material, each section having a shoulder set back from said edge, a slide embracing all of such sections at the four said shoulders thereof, one part of said slide being approximately as

35 wide as the sum of the widths of two of the thickened sections of the two strips between their opposed shoulders when the two strips are in connected relation, another part of the slide having diverging side walls confining

40 each of the sections from its shoulder to its free edge during the stage where the two strips are in disconnected relation, and means situated between the opposite sections of each strip adapted to form an interlock as the action of the slider walls against the shoulders

45 of the thickened sections forces the latter into parallel relation.

28. A fastener structure comprising two supporting strips, each having associated

50 therewith, a thickened rubber-like section arranged for mating contact, complementary interlocking structures concealed within said sections when mated and comprising a row of elements within the edge portion of one of

55 said sections, said elements having projections thereon, and a row of elements having receiving and retaining recesses in the other of said sections, said last named row being defined at least in part by elements composed of

60 material more rigid than said rubber-like sections and embedded within, supported in proper position by, and anchored in the confines of the rubber section and extending transversely of the row, whereby each of the

65 successive recesses is bounded lengthwise of

the row by two such rigid elements, said supporting sections adapted to be manipulated for effecting interlock therebetween by the coercive action of a slide against the rubber sections.

In testimony whereof I affix my signature.
